CLAIM

(21) Appl. No.: **29/421,130**

The ornamental design for a system design for sending a digital signal, and receiving the signal at a remote location, as shown and described.

(22) Filed: **May 29, 2012**

DESCRIPTION

(51) **LOC (10) CL.** **01-05**

FIG. 1 is a perspective view from the front of the sending unit of my new system design.

(52) **U.S. CL.**

FIG. 2 is a perspective view from the front of the receiving unit of my new system design.

USPC **D10/104.1**

FIG. 3 is an elevational view of the front cover of the sending unit shown in FIG. 1.

(58) **Field of Classification Search**

FIG. 4 is a side elevational view of the back plate of the sending unit shown in FIG. 1.

USPC D10/104.1, 104.2, 106.1; D13/168;

FIG. 5 is an opposite side elevational view thereof.

D14/137, 138, 155, 217; 340/426.17,

FIG. 6 is an elevational view of the back plate of the sending unit shown in FIG. 1.

340/426.19, 426.21, 426.24, 426.25,

FIG. 7 is a top plan view thereof.

340/539.15, 573.1, 573.4, 601; 455/575.1

FIG. 8 is a bottom plan view thereof.

See application file for complete search history.

FIG. 9 is a front elevational view of the receiving unit of my new system design.

(56) **References Cited**

FIG. 10 is a side elevational view of the receiving unit shown in FIG. 9.
